WEATHERSTRIPPING

Alexander F. Littmann, 963 Fellowship Road,
Santa Barbara, Calif. 93105

Filed June 19, 1972, Ser. No. 264,001

Term of patent 14 years

Int. Cl. D25—01

U.S. Cl. D13—6

FIG. 1 is a front perspective view of weatherstripping embodying my new design;

FIG. 2 is a back perspective view thereof;

FIG. 3 is a sectional view taken along line 3—3 in FIG. 1;

FIG. 4 is a front perspective view of an alternative embodiment of my new design;

FIG. 5 is a back perspective view thereof; and

FIG. 6 is a sectional view taken along line 6—6 in FIG. 4.

I claim:

The ornamental design for a weatherstripping, substantially as shown and described.
